Thomas Nibl, Newarkville, Ohio.

Letter Patent.

The schedule referred to in these Letters Patent and making part of the same containing a description in the words of the said Thomas Nibl himself of his improvement in the trap for catching Rats and other animals.

Be it known that I, Thomas Nibl of Newarkville, Licking County, State of Ohio have made an improvement in a trap for catching rats and other animals which is described as follows, reference being had to the annexed drawings of the same making part of this specification.

This trap consists of a Box (a) about six feet long and six inches square open at both ends having a drop or gate (b) at each end sliding in grooves or grooves cut in the side pieces of the box, which gates are raised and held up by cords (c,) attached to the upper ends thereof passing through apertures in the ends of two posts (d) cut into the top of the box near the ends of the same and leading through another aperture made in the end of a post (e) inserted into the side of the box, near the center of the same, from which it leads to a trigger (f,) to which it is fastened and one end of the trigger being set in a notch (g) cut in the last mentioned post and the other end set in a notch (h), and in the end of the last post (i) passing through an opening (j), made in the side of the box directly under the middle post, which last post has a notch (k) near its center which is set against the side of the opening just mentioned, The openings must all be lined with tin around their edges. The drawing

represents the trap as set.

Before setting the trap the gates are to be propped up so as during a period of time sufficient to accustomed the rat to pass in and out of the trap without molestation. The traps are then covered the fork baited and the trap set as before described. the rats of course will be taken alive and will not be supposed to be killed within the trap because it has been found that rats will not enter so freely a trap in which others have been killed as otherwise. They must therefore be discharged at one run by a rammer such as is represented at (b) and then destroyed by dogs or in some other manner. To catch muskrats a mirror (m) must be put on the inside of one of the gates with a light (n) let into the top of the trap above the mirror. The mirror is for the purpose of deceiving the muskrat by his own image, another mode of contrivance being a trap is by having a slide with looking glasses on each side placed in the centre of the trap having two triggers and wire guides as represented in the annexed drawings (fig. 3) this forming two traps.

What I claim as my invention & which I desire to have Letters Patent consist in the device described herein for catching rats and other animals. I do not claim the use of the looking glass in traps.
